AERATOR FOR A SEWAGE SYSTEM

David S. MacLaren, 21176 Brantley Road,
Shaker Heights, Ohio 44120

Original design application Apr. 17, 1974, Ser. No. 461,493, now Patent No. 237,007, which is a continuation of abandoned design application Ser. No. 276,078, July 28, 1972. Divided and this application May 12, 1975, Ser. No. 576,452

Term of patent 14 years

Int. Cl. D15—99; D23—01
U.S. Cl. D55—1 D

FIG. 1

FIG. 2

FIG. 3

FIG. 4

FIG. 5

FIG. 6

FIG. 1 is an elevational view of an aerator for a sewage system embodying my new design;

FIG. 2 is a top plan view thereof;

FIG. 3 is a bottom plan view thereof;

FIG. 4 is an elevational view taken 90 degrees from FIG. 1;

FIG. 5 is an elevational view taken 90 degrees from FIG. 4; and

FIG. 6 is an elevational view taken 90 degrees from FIG. 5.

This is a division of design application Ser. No. 461,493, filed Apr. 17, 1974, now Design Pat. No. D. 237,007, issued Sept. 30, 1975, which was a continuation of design application Ser. No. 276,078, filed July 28, 1972, now abandoned.

I claim:

The ornamental design for an aerator for a sewage system, substantially as shown.
